Primary Examiner — Richard E Chilcot(74) *Attorney, Agent, or Firm* — Oliff PLC(57) **CLAIM**

The ornamental design for an optical fiber connector, as shown and described.

DESCRIPTION

FIG. 1 is a front, left-side, top perspective view of the optical fiber connector;

FIG. 2 is a top plan view thereof;

FIG. 3 is a bottom plan view thereof; and,

FIG. 4 is a left-side elevational view thereof, the right-side elevational view (not provided) being a mirror image thereof.

The broken lines depict parts of the optical fiber connector that form no part of the claimed design.

1 Claim, 4 Drawing Sheets(56)
